UNITED STATES PATENT OFFICE.

GUSTAV E. FRITZ, OF CHICAGO, ILLINOIS, ASSIGNOR OF ONE-HALF TO HAROLD J. BANKS, OF CHICAGO, ILLINOIS.

METAL BACKING FOR TEETH.

1,129,476.

Specification of Letters Patent. Patented Feb. 23, 1915.

Application filed July 20, 1914. Serial No. 851,953.

To all whom it may concern:

Be it known that I, GUSTAV E. FRITZ, a citizen of the United States, a resident of Chicago, in the county of Cook and State 5 of Illinois, have invented new and useful Improvements in Metal Backings for Teeth, of which the following is a specification.

This invention has reference to an improvement in metal-backings for porcelain teeth, which have a pin or pins baked in 10 the porcelain, and known as "pin teeth."

That the invention may be more fully understood, reference is had to the accompanying drawings forming a part of the specification, in which:—

Figure 1 is a vertical sectional view through a porcelain pin facing, also showing my improved metal tube or cylinder for the pin or pins, and the backings, the same 20 being in detached relation; Fig. 2 is a transverse sectional view through the facing, showing the metal tubes or cylinders on the pins, and the backing burnished in position on the facing, and Fig. 3 is a view similar to 25 Fig. 1, with the parts assembled and soldered.

Like characters of reference denote corresponding parts throughout the figures.

1 denotes a porcelain facing having the 30 pins 2 baked therein, the same having been ground at the incisal edge, as at 3 so as to have a protecting tip of metal, when the backing has been attached.

4 designate metal tubes or cylinders, 35 closed at one end, as at 5, and with annular flanges 6 formed at their open ends. These tubes or cylinders are adapted to cover the pins 2, with their flanges bearing against the posterior of the facing.

40 7 denotes a backing preferably of pliable or flexible metal, having a hole or holes 8 therethrough, corresponding to the number of pins on the facing and only large enough to allow the tubes or cylinders to pass there- 45 through, when the backing is applied to the facing.

In making up a case, the incisal edge of the facing is preferably beveled, as at 3; the tube or tubes 4 then fitted over the pin or pins 2, with the flanges 6 bearing against 50 the posterior face of the facing and the backing 7 passed over the tubes 4 and burnished over and against the flanges 6, so as to rest thereagainst, and also against the posterior face of the facing with a portion 55 burnished over the ground incisal edge 3, as at 9, so as to give a protecting tip to the incisal edge. Sticky wax is applied to the backing 7 and tubes 4 so that they will be held in correct relation while the facing is 60 removed. After removal, the backing and tubes are invested in an investment material, heat applied, and solder 10 made to flow over the backing and tubes. The facing 65 may then be cemented to the backing. The 70 flanges 6 on the tubes 4 will prevent solder from flowing on the reverse side of the backing, and also serve to hold the backing in correct relation and prevent dislodgment of the plate on the tubes when removed from the facing for investment.

What I claim is:—

1. In an artificial tooth, in combination, a tooth, a pin or pins baked in the tooth, a tube to cover each pin, said tubes closed at 75 one end and having annular flanges at their open ends to rest against the tooth and a backing for the tooth, said backing having openings to receive the tubes and adapted to rest against the flanges on the tubes, for the 80 purposes specified.

2. A backing for a pin tooth, including a tube to cover the pin, said tube having one end closed and an annular flange at its open end, and a backing plate of pliable metal 85 having an opening to adapt the plate to be passed over the tube and rest against the flange on the tube.

GUSTAV E. FRITZ.
